UNITED STATES PATENT OFFICE.

CLARENCE B. HARBISON, OF LIMA, OHIO, ASSIGNOR TO THE OHIO STEEL FOUNDRY COMPANY, OF LIMA, OHIO, A CORPORATION OF OHIO.

EQUALIZER TRUCK.

Application filed February 6, 1928. Serial No. 252,173.

This invention relates to improvements in railway truck frames and more particularly to four-wheel equalized trucks, and has for its principal object to provide an improved construction and arrangement of the frame and equalizer bars between each pair of wheels at opposite sides of the truck, whereby the load is effectively distributed in an improved manner, as will hereinafter 10 more fully appear.

The invention may best be understood by reference to the accompanying drawing in which Figure 1 is a partial side view of a truck frame constructed in accordance with 15 my invention.

Figure 2 is a section taken on line 2—2 of Figure 1 and

Figure 3 is a detailed section on line 3—3 of Figure 1.

Referring to details shown in the drawings, Figures 1 and 2 show only a fragmentary portion of a four-wheel truck including the supporting members for one wheel, but it will be understood that the construction 25 of other portions of the frame is carried out in the same manner as the portions herein shown and described.

The truck frame includes a side frame 10 and a transverse bolster 11, connected with 30 the opposite side of the frame member and upon which the car is pivotally supported at its center in the usual manner. Pedestals 12 are mounted on the ends of the side frame members 10, said pedestals, side frame members 35 and transverse bolster all being preferably formed of a hollow single piece casting. The wheels are journalled in the pedestals in the usual manner as indicated in dotted lines.

A pair of equalizer bars 13, 13, extend in parallel relation on opposite sides of the pedestals and side frame member, each of 40 said equalizer bars consisting of an upwardly offset portion 14 which engages directly on the journal box (not shown), a downwardly extending portion 15 along the inner side of 45 the pedestal 12, and a transverse portion 16 spaced below the side frame member 10. Said equalizer bars are completed at their 50 opposite end by similar downwardly extending portions 15 and offset horizontal portions 14 in supporting engagement with the companion journal box on the same side of the frame.

An auxiliary suspension bar 17 is mounted 55 between the two main equalizer bars 13, 13, and is connected at opposite ends to said bars at points adjacent the upwardly extending portion 15 thereof, closely adjacent the pedestal 12. In the form shown said 60 auxiliary bar 17 is connected by means of a removable pin 18 extending through boss 19 of bar 17, and the two bars 13, 13, as clearly shown in Figures 1 and 3. The load imposed directly on the frame is carried on the 65 axles through a plurality of springs 20, 20, at the center portion of the side frame 10 and resting on the auxiliary bar 17, and through the equalizing bars 13, 13, to the journal boxes. In the form shown, the 70 springs 20, 20, are of the leaf type, although it will be understood that other types of springs, as for instance coil springs, might be utilized at this point if desired.

Among the advantages of a truck constructed as above described is the extreme simplicity of design wherein but single sets of springs 20, 20, at opposite sides of the frame is required, and the load is effectively 75 equalized upon all four wheels. It will be 80 observed that the lateral thrusts are mainly taken up by the truck frame itself through the side frame members 10 and pedestals 12, but freedom of relative vertical movement of the equalizer bars 13, 13, and auxiliary 85 bar 17 in a vertical direction is afforded as said equalizer bars respond to variations of vertical deflection of the springs.

It will be seen further that the provision of an auxiliary equalizer bar 17 connected at 90 opposite ends to points adjacent the pedestals relieves the two equalizer bars 13, 13, of much of the bending moment which otherwise would be imposed upon them immediately under the springs. The equalizer 95 bars may therefore be of reduced height adjacent the center and furthermore may be of substantially uniform thickness or width throughout their length so as to be readily formed out of bar stock, rather than requiring a more massive and complicated structure which otherwise would be required for these parts. This arrangement also permits the truck frame proper to be jacked or raised for 100 replacing the springs or other similar repairs, by withdrawing the pins 18, 18, which secure the ends of the auxiliary bar 17 between the two equalizer bars 13, 13.

While I have illustrated and described certain embodiments of my invention, it will be understood that I do not wish to be limited to the exact construction shown and described, but that various changes and modifications may be made without departing from the spirit and scope of my invention.

I claim:

1. In a railway truck, a main frame member including a transverse bolster, side frame members and pedestals integral therewith, a pair of equalizer bars disposed on opposite sides of each of said frame members and having their outer ends in direct supporting engagement with journal boxes on the same side of said frame, said equalizer bars being downwardly offset along their center portions, and an auxiliary bar disposed between the center portions of each pair of equalizer bars, and having each of its ends connected to said equalizer bars short of its adjacent pedestal, and springs interposed between

each of said auxiliary bars and their respective side frame member thereabove.

2. In a railway truck, a main frame member including a transverse bolster, side frame members and pedestals integral therewith, a pair of equalizer bars disposed on opposite sides of each of said frame members and having their outer ends in direct supporting engagement with journal boxes on the same side of said frame, said equalizer bars being downwardly offset along their center portions, and an auxiliary bar disposed between the center portions of each pair of equalizer bars, and having each of its ends connected to said equalizer bars short of its adjacent pedestal, and springs interposed between each of said auxiliary bars and their respective side frame member thereabove.

Signed at Lima, Ohio, this 1st day of February, 1928.

CLARENCE B. HARBISON.
